DESIGN FOR A WEDDING RING

Albert Samuels, San Francisco, Calif.

Application March 31, 1934, Serial No. 51,275

Term of patent 3½ years

To all whom it may concern:

Be it known that I, ALBERT SAMUELS, a citizen of the United States, residing at the city and county of San Francisco, State of California, have invented a new, original, and ornamental Design for a Wedding Ring, of which the following is a specification, reference being had to the accompanying drawing, forming part thereof, in which

Fig. 1 is a perspective view of a wedding ring showing my design.

Fig. 2 is a section through line 2—2 of Fig. 1.

I claim:

The ornamental design for a wedding ring, substantially as shown.

ALBERT SAMUELS.
